COMPRESSIVE WAVE TRANSMITTING OR RECEIVING DEVICE

Edwin E. Turner, Jr., West Roxbury, Mass., assignor, by mesne assignments, to Submarine Signal Company, Boston, Mass., a corporation of Delaware

Application July 29, 1942, Serial No. 452,808

7 Claims. (Cl. 177—386)

1

The present invention relates to an acoustical transducer of a resonant or non-resonant type operable at high or low frequencies or over a considerable frequency range.

In the present invention two coupled systems are employed, each of which may have differently or similarly tuned resonant characteristics. In the present invention the coupling in the device is so established that the force factor enhances the adaptability of the device for transmission of compressional waves through a liquid, preferably a water medium.

A further feature in the present system is that the electrical energy works at the end of a longitudinally vibrating system where the mechanical motion is large while the acoustic vibrations are derived from longitudinal vibrations having a reduced vibrational amplitude. In this form of the invention the radial vibrations of the longitudinally vibrating element, preferably the vibrations near the longitudinal node, are used to produce radial vibrations of a tube or shell whose external surface is exposed to the compressional wave-propagating medium.

The invention will be more fully described in connection with the specification below when taken in connection with the drawing illustrating the same in which Fig. 1 shows a longitudinal section of one form of the device, Fig. 2 shows a similar view of another modification and Fig. 3 shows a force diagram of the operation of the apparatus.

In the modification shown in Fig. 1 there is provided an external cylinder whose principal form of radiation is radially from the surface of the cylinder to the sound propagating medium. This cylinder comprises a magnetic steel tube 30 having an inwardly projecting ring or boss 31 located midway between the ends of the cylinder. The cylindrical tube 30 may also be provided with grooves 32 and 33 located at the same distance from the ends of the cylinder serving to permit vibration free from the end effect of the caps on the tube. The ends themselves may be made watertight in any usual manner, as, for instance, indicated in the figure by the use of a rubber disc 34 which is squeezed outwardly against the inner walls of the cylinder between two plates 35 and 36. Within the cylinder 30 there is positioned a copper tube 31 which is expanded to fit snugly against the projecting ring 31 from the inside of the cylinder. This copper tube is preferably supported this way at its midpoint and, in fact, the whole structure is symmetrical at either side of the boss or inwardly projecting ring 31. Within the copper tube 31 there is provided a "Bakelite" core 38 which is supported by a centrally positioned "Alnico" or other high magnetic permeable rod 39 which is itself supported by the end plug elements as indicated in Fig. 1. At each end of

2

the "Bakelite" core there are provided flanges 40 of soft iron which have their cylindrical peripheries recessed to receive coils 41 and 42 which may be energized by alternating current from the leads 44 and 45.

The magnetic circuit is therefore established through the "Alnico" central core, the soft iron flanges and the external magnetic steel tube 30. This sets up radial airgaps at the ends of the magnetic steel tubes on the inside just within the position of the grooves 32 and 33. Alternating current flowing through the coils 41 and 42 establishes current in the copper aluminum or alloy tube 37 which provides longitudinal motion or vibration of the copper tube. By making the copper tube one-half wave length in the material, a longitudinal resonance will be established. Similarly, a longitudinal resonance may be established in the steel tube 30 but this is made preferably to have a resonance for radial vibration. Energy is transferred from the vibration of the copper tube to that of the steel tube through the inwardly extending central boss 31 since longitudinal expansion and contraction of the copper tube is accompanied by radial contraction and expansion at the center of the copper tube adjacent the ring or boss member 31.

A diagram of the operation of the system is indicated in Fig. 3 in which the tube 37 is indicated by the dotted line L₁ as vibrating in longitudinal resonance with an expansion and contraction in the center section as indicated by the dotted lines T₁. This vibration in the central section will be in a direction perpendicular to the direction of the longitudinal vibrations of the tube. The transverse vibration is indicated by T and the longitudinal vibration by L. When the tube 37 contracts in a longitudinal direction, its central section expands in the direction of the arrows T and this expansion produces an outward radial motion of the shell 30, as indicated by the dotted line R₁, in the direction of the arrow R. As indicated in Fig. 3 the vibration is maximum at the center and tapers off to the edges as shown in the figure.

The system described in this invention comprises in this respect a double resonant system in which the two elements are loosely coupled to each other and therefore the resonance of one has only a slight effect on the resonance of the other and each might be independently tuned in making the apparatus. In this invention also the outer steel tube 30 is preferably made heavier than the inner tube 37 which is made to vibrate by the induced electrical current from the coil 42. By properly choosing the mass ratio between the tube 31 and the steel tube 30, it is possible to transform the amplitude of vibration so that a large force factor may be available at the water surface and therefore the electrical driving tube,

namely the tube 31, may be operated in its most efficient manner at resonance.

The same arrangement employing a magnetostrictive drive is shown in Fig. 2. In this case a cylindrical tube 1 is provided with similar grooves 2 and 3 as the structure previously described and an inwardly projecting boss 4 located midway between the ends of the tube. In this modification the tube bearing against the boss 4 comprises a nickel tube 5 and it also should be noted that the outer tube 1 is of non-magnetic material. The magnetic circuit is similar as in the case of the previous modification with a central "Alnico" core 6 and soft iron end flanges 7 and 8 which, however, are not recessed as in the other figure. The leads 9 and 10 connect to a coil 11 wound around the Bakelite core 12 and this coil provides an alternating flux for the magnetic circuit which now comprises the Alnico core 6, the end flanges 7 and 8 and the nickel tube 5, the flux running longitudinally in the nickel tube. The alternating flux applied in this way produces longitudinal vibrations of the nickel tube and these vibrations in the manner which has been described in connection with the other figures produce radial vibrations of the outer tube 1.

The radiation into the water medium is obtained in the present case also preferably by the radial vibrations of the outer cylinder since there is no water load provided on the ends of vibrating tubes so that the energy in the present case is radiated by means of the radial expansion and contraction of the external tubes. If the external tubes are less than one half a wave length long or one-half wave length long, radial vibration will be produced by the tubes with the portions directly over the bearing sections 4 and 31 having the greatest amplitude of motion and the amplitude at the ends of the tubes adjacent the groove section being substantially less. The construction of the device may further be so made that the tube is tuned for radial vibration rather than for longitudinal vibration. This may be accomplished in the usual well-known manner and will also provide a coupled system between two coupled resonant structures in which the inner electrically operated member will be vibrated with a free large amplitude.

Having now described my invention, I claim:

1. A compressional wave transmitting or receiving device comprising an elongated hollow cylinder having a centrally located internally projecting boss, a second cylinder aligned within the first cylinder and supported by said boss, and means for longitudinally vibrating said second cylinder and producing thereby radial vibrations of said first cylinder.

2. A compressional wave transmitting and receiving device comprising an elongated hollow cylinder having a centrally located internal projecting boss, means sealing the ends of the cylinder from the compressional wave-propagating medium, a second cylinder aligned within the first cylinder and supported by said boss, and means for longitudinally vibrating said second cylinder and producing thereby radial vibrations of the first cylinder.

3. A compressional wave transmitting and receiving device comprising an elongated hollow cylinder having a centrally located internal projecting boss, means sealing the ends of the cylinder from the compressional wave-propagating medium, a second cylinder aligned within the

first cylinder and supported by said boss, and means for longitudinally vibrating said second cylinder and producing thereby radial vibrations of the first cylinder, said first cylinder having near its ends deep grooves permitting free radial motion of the portions of the cylinder between said grooves.

4. A compressional wave transmitting or receiving device comprising an elongated hollow cylinder having a centrally located internally projecting boss, a second cylinder aligned within the first cylinder and supported by said boss, means for longitudinally vibrating said second cylinder and producing thereby radial vibrations of said first cylinder, said means including means for establishing a magnetic field in the region at the ends of the second cylinder, and means inducing a variable electric current in the ends of said second cylinder for longitudinally vibrating the same.

5. A compressional wave transmitting or receiving device comprising an elongated hollow cylinder having a centrally located internally projecting boss, a second cylinder aligned within the first cylinder and supported by said boss, means for longitudinally vibrating said second cylinder and producing thereby radial vibrations of said first cylinder, said means including means for establishing a magnetic field in the region at the ends of the second cylinder, and means inducing a variable electric current in the ends of said second cylinder for longitudinally vibrating the same, said second cylinder being tuned longitudinally at the electrical vibrating frequency.

35 6. A compressional wave transmitting or receiving device comprising an elongated hollow cylinder having a centrally located internally projecting boss, a second cylinder aligned within the first cylinder and supported by said boss, means for longitudinally vibrating said second cylinder and producing thereby radial vibrations of said first cylinder, said second cylinder being of magnetostrictive material, and said last means including means for producing flux variations in said second cylinder whereby said vibrations are produced.

7. A compressional wave transmitting or receiving device comprising an elongated hollow cylinder having a centrally located internally projecting boss, a second cylinder aligned within the first cylinder and supported by said boss, means for longitudinally vibrating said second cylinder and producing thereby radial vibrations of said first cylinder, said second cylinder being of magnetostrictive material, and said last means including means for producing flux variations in said second cylinder whereby said vibrations are produced, said second cylinder being tuned for longitudinal resonance at the frequency of said flux variations.
